(57) **CLAIM**

The ornamental design for a LED flashlight as shown and described.

DESCRIPTION

FIG. 1 is a front view of a LED flashlight, showing our new design;

FIG. 2 is a back view of the LED flashlight;

FIG. 3 is a left view of the LED flashlight;

FIG. 4 is a right view of the LED flashlight;

FIG. 5 is a top view of the LED flashlight;

FIG. 6 is a bottom view of the LED flashlight; and,

FIG. 7 to FIG. 14 are eight perspective views of the LED flashlight.

The broken lines in the drawings depict portions of the LED flashlight that form no part of the claimed design.

1 Claim, 7 Drawing Sheets
